UNITED STATES PATENT OFFICE.

HENRY MACARTHY, OF NEW YORK, N. Y., ASSIGNOR TO AMERICAN CAN COMPANY, OF NEW YORK, N. Y., A CORPORATION OF NEW JERSEY.

SHEET-METAL CAN.

No. 811,648.

Specification of Letters Patent.

Patented Feb. 6, 1906.

Application filed May 31, 1905. Serial No. 262,976.

To all whom it may concern.

Be it known that I, HENRY MACARTHY, a citizen of the United States, residing in the borough of Brooklyn, city of New York, in the county of Kings and State of New York, have invented a new and useful Improvement in Sheet-Metal Cans, of which the following is a specification.

My invention relates to improvements in sheet-metal cans, and more particularly to improvements in cans of large diameter, intending for containing and shipping heavy articles, such as ink, and having a deep tight-fitting flange slip-cover.

Heretofore in the cans to which my invention relates when the cover has been once removed the mouth of the can becomes distorted because of the heavy contents of the can and difficulty is experienced in replacing the cover as required, the operation being somewhat like that of the joining sections of stove-pipe owing to the large diameter of the can and the flexibility of its mouth.

The object of my invention is to overcome these difficulties or objections; and it consists in the means I employ to practically accomplish this object or result, as herein shown and described.

In the accompanying drawings, forming a part of this specification, Figure 1 is a top or plan view of a sheet-metal can embodying my invention. Fig. 2 is a vertical section on line 2 2 of Fig. 1. Fig. 3 is an enlarged detail vertical section. Fig. 4 is a detail horizontal section on line 4 4 of Fig. 2. Fig. 5 is a detail horizontal section on line 5 5 of Fig. 2, and Fig. 6 is a detail perspective view showing the two parts of the side seam of the can-body disconnected.

In the drawings, A represents the can-body of a sheet-metal can of large diameter embodying my invention, the same having a lap side seam a, formed by the overlapping meeting ends a' a' of the can-body blank, which are duly soldered together. This lap side seam extends over the whole vertical length of the can-body.

B is the bottom head of the can, the same being united to the lower end of the can-body by any suitable seam b. The seam b, as indicated in the drawings, is a double seam; but it may be of any other desired form, soldered or otherwise.

D is the sheet-metal cover, the same having a deep flange d, preferably from one-half 55 an inch to three-quarters of an inch in width or depth.

The sheet-metal can-body A is provided at its upper end with a downwardly-projecting external fold a³ and an upwardly-projecting 60 external fold a⁴, having an outwardly-turned edge or roll a⁵. The wide integral folds a³ a⁴ of the can-body makes the can-body of three thicknesses and furnishes it with two stiffening and strengthening rings, greatly adding to 65 the stiffness and rigidity of the can at its mouth or upper end and preventing it from becoming distorted when the slip-cover D is removed or when it is being removed and applied. The main body is further stiffened 70 and strengthened at its upper end by the turned edge or roll a⁵ at the upper edge of the outer ring or fold a⁴ and also by the curved portions a⁶ a⁷, which unites the fold or ring a³ with the can-body at the upper edge thereof 75 and the folds or rings a³ and a⁴ together. A narrow annular space is left between the downwardly-projecting fold or ring a³ and the upwardly-projecting ring or fold a⁴ to receive the flange d of the slip-cover D between 80 the folds or rings a³ and a⁴ and to afford a tight frictional fit or engagement between the flange of the slip-cover D and the integral folds or rings a³ a⁴ of the can-body. When the cover is applied, the upper end or mouth 85 of the can-body is thus composed of four thicknesses or rings at its upper end, which gives it the required strength and stiffness to resist all danger of distortion in handling and shipment of the cans even when filled with 90 the heaviest articles.

The cover D is provided with a ring D', preferably located near its rim or margin, for removing the cover. The cover D may also be provided with an annular depression d' at 95 its rim, which in connection with the marginal turned edge or roll a⁵ of the outer ring a⁴ of the can-body forms an annular groove or channel to receive paraffin or other adhesive substance f, which, if desired, may be applied to more tightly seal the can. The cover D is also preferably furnished with an external bead or horizontally-projecting bead or shoulder d', which tends to strengthen and stiffen the cover.

At the side seam of the can-body the meet-

ing ends of the wide folds or rings a^3 a^4 are securely soldered together, a^8 indicating the solder uniting the same.

I claim—

- 5 1. In a large-diameter can for containing heavy materials, the combination with a can-body having a wide integral downwardly-projecting fold or ring, and a wide integral upwardly-projecting fold or ring terminating in a roll at its upper edge, the meeting ends of said folds or rings abutting together and being united by solder, and the meeting edges of the can-body blank overlapping each other and soldered together at the side seam of the can-body, of a slip-cover having an integral wide flange tightly fitting between and engaging said integral folds or rings of the can-body, said outer integral fold or ring of the can-body having a roll at its upper edge
- 10 15 to facilitate the entrance of the flange of the cover between the same and said inner downwardly-projecting fold whereby the frictional engagement of the cover with the can-body is increased and the upper end or mouth of the can-body stiffened and strengthened and prevented from becoming distorted when the cover is being removed or replaced, substantially as specified.
- 20 25 2. In a sheet-metal can, the combination with a can-body having a plurality of external wide folds or integral rings at its upper end, said rings being united and abutting to-

gether at their meeting ends, and the meeting edges of the can-body blank overlapping each other and soldered together at the side seam of the can-body, of a cover having an externally-projecting shoulder or bead and a wide slip-cover flange fitting between and engaging said integral folds or rings of the can-body, said outer integral fold or ring of the can-body having a roll at its upper edge, substantially as specified.

3. In a sheet-metal can, the combination with a can-body having a plurality of external wide folds or integral rings at its upper end, said rings being united and abutting together at their meeting ends, and the meeting edges of the can-body blank overlapping each other and soldered together at the side seam of the can-body, of a cover having a wide slip-cover flange fitting between and engaging said integral folds or rings of the can-body, said outer integral fold or ring of the can-body having a roll at its upper edge, said cover having an externally-projecting shoulder or bead and an annular recess forming with said roll of said outer fold or ring of the can-body, a channel to receive a sealing material, substantially as specified.

HENRY MACARTHY.
